Primary Examiner — Dana Meyrow(74) *Attorney, Agent, or Firm* — Adam K. Sacharoff; Much Shelist, P.C.(57) **CLAIM**

The ornamental design for a bottle, as shown and described.

DESCRIPTION

FIG. 1 is a front left side perspective view showing the new design for a bottle;

FIG. 2 is a front right side perspective view thereof;

FIG. 3 is a rear left side perspective view thereof;

FIG. 4 is a rear right side perspective view thereof;

FIG. 5 is a front elevation view thereof, the rear elevation view being a mirror image thereof;

FIG. 6 is a left side view thereof, the right side view being a mirror image thereof;

FIG. 7 is a bottom plan view thereof; and,

FIG. 8 is a top plan view thereof.

The broken lines in the FIGS. form no part of the claimed design.
